UNITED STATES PATENT OFFICE.

ALBERT C. COBB, OF HOUSTON, TEXAS.

MAIL-DELIVERY APPARATUS.

1,366,401.

Specification of Letters Patent. Patented Jan. 25, 1921.

Application filed December 16, 1919. Serial No. 345,265.

To all whom it may concern:

Be it known that I, ALBERT C. COBB, a citizen of the United States of America, residing at Houston, in the county of Harris, and 5 State of Texas, have invented new and useful Improvements in Mail-Delivery Apparatus, of which the following is a specification.

The object in view is to provide a simple 10 and efficient means for facilitating the distribution and classification of mail matter directed to different destinations or destined to be handled by different carriers, under such conditions as to economize time and increase the accuracy with which such operations can be conducted in the rapid handling of mail matter, and to this end the invention consists in a construction and combination of parts of which a preferred embodiment is illustrated in the accompanying drawing, it being understood that changes 15 in form and proportion may be resorted to within the scope of the claims without departing from the principles involved.

25 In the drawing:

Figure 1 is a front view of an apparatus embodying the invention.

Fig. 2 is a side view of the same.

Fig. 3 is a detail sectional view of one of 30 the letter racks on the plane indicated by the line 3—3 of Fig. 1.

Fig. 4 is a similar view of the registered letter rack, the section being taken on the plane indicated by the line 4—4 of Fig. 1.

35 Fig. 5 is a detail horizontal section of one end of one of the racks on the plane indicated by the line 5—5 of Fig. 1.

Fig. 6 is a plan view of the apparatus.

Upon a suitable frame 10 consisting essentially 40 of uprights constituting guides or tracks of which any desired number may be arranged in series, one behind the other, are mounted carriages 11 having rollers 12 or similar anti-friction devices to facilitate the movement thereon upon the guides or tracks, and connected with each carriage is a counterbalancing device consisting of a weight 13 or the equivalent thereof, the connecting guard or cable 14 traversing suitably 45 positioned direction pulleys 15 so that either carriage may be brought within easy reach of the mail distributer, and a carriage mounted for example on the front guide or track may be moved out of the way to give 50 access to a carriage in the rear thereof or operating in a plane behind the foremost

carriage, so that a single distributer may be able to place mail matter in either of a plurality of carriages without inconvenience or loss of time.

Each carriage preferably supports a plurality of racks such as indicated at 16 and shown in detail cross section in Fig. 3 provided with terminal trunnions 17 mounted in frames 18 supported by the carriage.

These racks are reversible upon the terminal trunnions by means of crank arms or handles 19 and are provided at both sides with longitudinal seats 20 for the reception of mail matter, said seats being overhung 70 at the top and bottom by flanges 21 so that when a letter envelop is placed in front of a seat it may by mere pressure toward the seat be caused to spring at its edges under the flanges where it is held with the name 75 and address exposed. Obviously the reversal of a rack may be accomplished merely by a rapid movement of the crank or handle so as to give access to either side, so that mail for different destinations may be arranged on different sides of the same rack or one side may be exposed after the other has been filled. The racks are yieldingly held in either of the positions exposing the 80 seats or pockets on one side by means of a 85 stud 22 engaged with a spring latch 23. Said latch however is adapted to yield merely by applying sufficient strength to the crank or handle although adapted to maintain the rack in either of its adjusted positions against displacement by the act of inserting the letter envelops into the seats or pockets. Also preferably while the body 90 portions of the racks are designed for the reception of short or small letter envelops, enlarged receptacles or pockets 20^a may be provided at the ends thereof for the reception 95 of longer or legal size envelops.

Also preferably one of the racks is provided with closures 24 fitted with locking 100 means as indicated at 25 and adapted to cover the pockets or seats so as to adapt this particular rack for the reception of important mail such as registered letters.

It is furthermore obvious that as a guide 105 to the mail distributing operator suitable designations or indications of destination may be conveniently applied to the several racks as may be found desirable in practice.

What is claimed is:

1. A mail distributing apparatus having

a counter-balanced carriage, a plurality of reversible racks pivotally mounted upon the carriage and provided at opposite sides with letter receiving seats or pockets having over-
5 hanging flanges, and means for holding said racks in their adjusted positions.

2. A mail distributing apparatus having a carriage, reversible letter receiving racks mounted upon the carriage in pivotal relation thereto and provided with reversing
10

handles or cranks, and frictional means for holding said racks in their adjusted positions, the same consisting of studs on the racks and spring latches for engaging the studs, said racks being provided at opposite 15 sides with letter receiving seats or pockets.

In testimony whereof he affixes his signature.

ALBERT C. COBB.
